UNITED STATES PATENT OFFICE.

JOSEPH E. STRAKER, JR., OF ATTLEBORO, MASSACHUSETTS.

DESIGN FOR A HANDLE FOR SPOONS, FORKS, OR SIMILAR ARTICLES.

No. 38,828.

Specification for Design.

Patented Sept. 24, 1907.

Application filed August 14, 1907. Serial No. 388,563. Term of patent 7 years.

To all whom it may concern:

Be it known that I, JOSEPH E. STRAKER, Jr., a citizen of the United States, and residing in Attleboro, in the county of Bristol and Commonwealth of Massachusetts, have invented a new, original, and ornamental Design for the Handle of a Spoon, Fork, or Similar Article, which is illustrated in the accompanying drawing, forming part of this specification.

What I claim is:—

The ornamental design for the handle of a spoon, fork or similar article as shown.

JOSEPH E. STRAKER, JR.
